POLISHING APPARATUS

Joseph Stuart, II, Wilmington, Del., assignor to
Hercules Powder Company, Wilmington, Del., a
corporation of Delaware

Application December 19, 1940, Serial No. 370,801

8 Claims. (Cl. 91—53)

This invention relates to the production of polished insulated wire adaptable for use in electric blasting caps and more particularly to the method of polishing impregnated insulated wire and the apparatus therefor.

Wire used for conducting electric current in most instances is covered with insulating material, for example, cotton servings, paper, or similar material, and the insulated wire then impregnated with a non-conducting material usually paraffin wax which may contain other ingredients, such as rosin, carnauba wax, wax like substances, etc., in order to obtain special physical properties.

Wire insulated and impregnated as above may be used per se but in order to aid in handling and to improve appearances this wire may be polished. The known polishers usually include a revolving polishing head which has an adjustable chuck face that may be tightened upon the wire in order to polish the wire as it is pulled therethrough. This type polisher does not give high rates of production as there is a tendency for the wire to break and breakage requires continual rethreading of the machine. There is always a break in the wire whenever a knot or splice goes into the machine. Thus, the machine requires constant attention.

It is the object of this invention to provide an improved polishing device.

A further object of this invention is to provide a polisher which has no moving parts.

A further object of this invention is to provide a polisher which will allow the passage of knots and splices.

A further object of this invention is to provide a polisher which will have a high capacity of production.

A still further object of this invention is to provide an improved method of polishing wire.

Other and further objects will become apparent hereinafter upon an understanding of the description and drawing about to be presented.

The objects of this invention are accomplished by a polishing device having no moving parts but which is so constructed as to effect polishing of impregnated wire upon passage by drawing of the wire therethrough. The device includes a pair of supporting members interconnected with each other and which have mounted upon each member a plurality of polishing members aligned in a staggered and overlapping manner which will exert upon the wire at intervals on opposite sides thereof sufficient pressure to effect polishing.

Having now indicated in a general way the construction and purpose of this invention, there follows a more detailed description thereof with reference to the accompanying drawing in which:

Fig. 1 represents an elevation view of the device with an electrical conductor passing therethrough.

Fig. 2 represents a sectional view along line 10 2—2 of Fig. 1, and

Fig. 3 represents a prospective view of the polishing end of a polishing member.

Referring now to the figures and more particularly to Fig. 1, the polishing device of this invention includes an upper supporting member 1 and a lower supporting member 2 interconnected by adjustable means shown in the form of bolts 4. Attached to the supporting member 1 is a plurality of polishing members 5 by means 15 of bolts 6 which are adapted to provide positive and fixed clamping of the members 5 to the supporting member 1. Means 6 may if desirable be supplemented by an additional screw or bolt or by a recess or projection to insure positive 20 clamping of the polishing members 5. There is also a plurality of polishing members 7, similar to members 5, attached to supporting member 2 by for example bolts 9, similar to bolts 6.

The polishing members 5 and 7 are so arranged that their polishing faces are approximately aligned but staggered and overlapped with relation one with another. The polishing faces of members 5 and 7 contain a concavity 10 (Fig. 3) or groove through which an electrical conductor 11 passes. The conductor 11 is drawn through the staggered overlapping polishing members by any convenient means, such as for example, a gear driven reel having a traversing screw to cause even winding of the polished wire thereon. The speed of the take-off reel may be altered to effect the most efficient polishing.

The overlapping of the polishing heads may be varied when various gauge wire is being polished and also if desirable the size of the polishing 45 grooves may be altered to accommodate various gauge wire or various thickness of insulation. Likewise, the number of polishing members attached to each supporting member 5 may be varied to effect more efficient polishing action.

Polishing of impregnated wire is best accomplished by the device of this invention by starting with a wire having a slight excess of saturant on the surface thereof and drawing this wire through the device under tension. The overlapping 50 arrangement of the polishing members cre-

ates a pressure on each side of the wire and polishes the saturant to a smooth and glossy finish. The gloss obtained depends upon the saturant used but a saturant containing a high percentage of paraffin wax will give a very desirable polish. Additions to the saturant of waxes such as carnauba, montan and the like aids high gloss.

In operating the polishing device, the staggered effect must not be too close together and the overlapping should not offer too high resistance to pulling of the wire through the polishing heads as each item will tend to cause breakage whenever a knot passes and will cause abrasion of the insulation.

Since the amount of wax left on the wire is in part determined by the contact of the polishing head and grooves, it is advantageous and desirable to regulate the off-line position of the heads so that the desired results are obtained.

Further, the polishing heads are overlapped slightly so that any excess impregnation composition which is removed depends upon the friction of the wire against the heads, however, too much friction will tend to give a rough surface so that the heads are adjusted to give desired results. For example, the first pair of heads may overlap considerably while subsequent heads are not overlapped as much thereby allowing a light pressure to be exerted upon the wire when it passes the last pair of polishing heads which will give an exceptionally high polish.

It will be understood that the polishing device of this invention may be used for polishing wire impregnated and stored prior to polishing or may be positioned so that the wire coming from a impregnation step is passed therethrough and polished. Polishing to high smoothness and gloss requires the saturants on the wire to be hard, therefore, if wire direct from the impregnation step is to be used it must be passed through a cooling device for best results.

The simplicity of operation and ease of adjustment of the polishing device of this invention which results in a higher production rate over prior art machines is realized in part by the quick manner in which the wire 11 is moved into polishing position. The wire 11 which may be supplied from any suitable source as, for example, a reel, not shown, may be moved into polishing position between the polishing elements 6 and 7 from one side thereof and then onto a suitable take-up reel not shown. It is noted that the threading operation may be accomplished with both ends of the wire in position.

The advantages of the polishing device of this invention is in the simplicity of operation, ease of adjustment, lack of breakage of the wire passing therethrough, high production rate and adaptability to various types of wires. The polished wires produced by this device find special use in the blasting cap industry, since the leg wires thereof must be smooth to facilitate handling and also should provide an appearance that is attractive. Polished wires give both of these properties.

It will be understood that the details and examples hereinbefore set forth are illustrative only and that the invention as broadly described and claimed is in no way limited thereby.

What I claim and desire to protect by Letters Patent is:

1. A device of the character described which includes in combination a wire polisher comprising a pair of substantially parallel supporting members, means interconnecting said members, 75

a plurality of polishing members adjustably secured to one of said supporting members, and a plurality of polishing members adjustably secured to the other said supporting member in staggered and overlapped relation to the polishing members on said first parallel member, whereby a wire passed therebetween has exerted thereon a polishing pressure.

2. A device of the character described which includes in combination a wire polisher comprising a pair of substantially parallel supporting members, means interconnecting said members, a plurality of polishing members adjustably secured to one of said supporting members, and a plurality of polishing members adjustably secured to the other said supporting member in staggered and overlapped relation to the polishing members on said first parallel member, said polishing members having a concavity for receiving, guiding, and polishing a wire passed therebetween, whereby said wire has exerted thereon a polishing pressure.

3. A device for producing polished leg wires adaptable for electric blasting caps which includes in combination a pair of substantially parallel supporting members joined by vertically adjustable means, two polishing members rigidly attached in space relationship with each other on one of said pairs of supporting members and a polishing member rigidly attached to the other said supporting member and extending into the space provided between the two polishing members attached to said first supporting member to give an overlapping relationship between the polishing members, whereby a polishing action will result upon passage of a wire under and over said polishing members.

4. A device for producing polished leg wires adaptable for electric blasting caps which includes in combination a pair of substantially parallel supporting members joined by vertically adjustable means disposed in a plane including said members, two polishing members having a concavity adaptable for receiving a wire to be polished rigidly attached in space relationship with each other on one of said pairs of supporting members and a polishing member having a concavity adaptable for receiving a wire to be polished rigidly attached to the other said supporting member and extending into the space provided between the two polishing members attached to said first supporting member to give an overlapping relationship between the polishing members, whereby a polishing action will result upon passage of a wire under and over said polishing members.

5. A device of the character described which includes in combination a wire polisher comprising a pair of substantially parallel supporting members, means adjustably interconnecting said members, a plurality of polishing members adjustably secured to one of said supporting members, and a plurality of polishing members adjustably secured to the other said supporting member in staggered and overlapped relation to the polishing members on the first said parallel member, whereby a wire passed therebetween has exerted thereon a polishing pressure.

6. A device for producing polished leg wires adaptable for electric blasting caps which includes in combination a pair of substantially parallel supporting members joined by adjustable means disposed in a plane including said members, a plurality of polishing members attached in space relationship with each other on one of said pairs of supporting members, and at least one polishing member attached to the other said supporting

member and extending into the space provided between two of the said plurality of polishing members attached to the first mentioned supporting member to give an overlapping relationship between the polishing members, whereby a polishing action will result upon passage of a wire under and over said polishing members.

7. A wire polishing device comprising a pair of stationary support members, means interconnecting said members and disposed in a plane including said members, a plurality of polishing elements secured to one of said support members, and a plurality of polishing elements secured to the other of said support members in staggered and over-lapped relation to the polish-

ing elements on said first support member, whereby a wire passed between said polishing elements has exerted thereon a polishing pressure.

8. A wire polishing device comprising a pair of stationary support members, adjustable means interconnecting said members and disposed in a plane including said members, a plurality of polishing elements secured to one of said support members, and a plurality of polishing elements secured to the other of said support members in staggered relation to the polishing elements on said first support member, whereby a wire may be moved into polishing position laterally relative to said plane.

JOSEPH STUART, II.
